[57] **CLAIM**

The ornamental design for an air suction cleaning device, as shown and described.

DESCRIPTION

FIG. 1 is a side elevational view of an air suction cleaning device showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is an isometric view thereof.

FIG. 7 is an isometric view of a second embodiment of the air suction cleaning device, wherein the only difference resides in the use of a single tank.

FIG. 1

FIG. 2

FIG. 4

FIG. 5

FIG. 3

FIG. 6

FIG. 7
